(57) **CLAIM**

The ornamental design for a medical powder spreading device as shown and described.

DESCRIPTION

FIG. 1 is a perspective view a medical powder spreading device showing our new design;

FIG. 2 is a front elevational thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken lines shown in FIGS. 1-7 illustrate portions of medical powder spreading device that form no part of the claimed design.
